UNITED STATES PATENT OFFICE.

JONAS LANGFELD, OF NEW YORK, N. Y., ASSIGNOR TO ABRAHAM M. LANGFELD AND MORRIS F. LANGFELD, TRADING AS LANGFELD BROS. & CO., OF PHILADELPHIA, PENNSYLVANIA.

CIGAR-CASE.

No. 894,892.

Specification of Letters Patent.

Patented Aug. 4, 1908.

Application filed December 14, 1907. Serial No. 406,420.

To all whom it may concern:

Be it known that I, JONAS LANGFELD, a citizen of the United States, and a resident of the city of New York, county of New York, 5 State of New York, have invented an Improvement in Cigar-Cases, of which the following is a specification.

My invention has reference to cigar cases, and consists of certain improvements, which 10 are fully set forth in the following specification, and shown in the accompanying drawings, which form a part thereof.

The object of my invention is to provide a pocket cigar case with means for keeping the 15 tobacco in a moist condition while in no wise interfering with the usual and normal use of the case.

My invention consists of a pocket case for 20 cigars of leather or equivalent material combined with a moisture pad secured therein in such manner as to permit the insertion and removal of the cigars in the usual manner.

More particularly, my invention resides in the combination of a cigar case, with a humidor 25 comprising a moisture pad and a metal holder therefor which has one or more extensions for attachment with the case.

My invention also comprehends details of 30 construction which, together with the features above specified, will be better understood by reference to the drawings, in which:

Figure 1 is a sectional elevation of a cigar case embodying my invention; Fig. 2 is a cross section of the same on line 2--2; Fig. 3 is an elevation of the humidor detached from 35 the case; Fig. 4 is a sectional elevation of a modified form of my invention; Fig. 5 is a cross section of part of same on line 5--5 of Fig. 4; Fig. 6 is a sectional elevation of a 40 lower part of a cigar case embodying another modification of my invention; Fig. 7 is an elevation of another style of cigar case to which my invention is applied; Fig. 8 is a cross section of same on line 8--8 but with 45 the case open; Fig. 9 is a perspective view of the humidor employed in the case shown in Figs. 7 and 8; and Fig. 10 is a cross section of the same on line 10--10.

Referring to Figs. 1, 2 and 3, A is the body 50 of the cigar case and is made of rectangular shape adapted for pocket use. As shown, it is open at the top. This case is usually made of soft leather.

B is a humidor frame having flanges b b

and supporting a pad F of absorbent material such as felt which is moistened with water when in use. The ends of this frame B are provided with spring arms E E which normally spread apart at their free ends, as shown in Fig. 3. This humidor is forced down to the bottom of the case and the spring arms rest against the inner end walls of the case. These arms are preferably made of flat sheet metal of a width approximately equal to the thickness of the case so that they act as stiffeners to the ends while the humidor frame B acts as a stiffener for the bottom part of the case. The spring action of the arms E E act to hold them snugly to the ends of the case and keep the humidor 60 in position. These arms also constitute means for raising the humidor from the case when it is required to remoisten it.

The specific construction of the humidor shown in Figs. 1, 2 and 3, consists of a flat 75 plate having inwardly directed side flanges b b which form a groove into which the moisture pad F of felt or other suitable porous material is placed. As shown in Fig. 2, these side flanges b may leave a gap between 80 them through which the pad F may be seen. It is immaterial, however, just how this framework which supports the moisture pad is formed, but the construction illustrated in these figures is exceedingly simple, effective, 85 and cheaply made.

In Figs. 4 and 5, the humidor is shown at B' and is arranged against one of the ends of the case instead of at the bottom, so that the cigars would be parallel to the humidor instead of at right angles to it, as indicated in Fig. 1. The humidor B' is provided with an arm E' extending from it and in this instance bent over at the top as at e to fit over the upper edge of the case A, whereby the humidor 95 may be held in proper position within the case and may be readily withdrawn from it when desired for purposes of remoistening it.

In Fig. 6, the humidor B² is shown as a small tubular vessel which fits into the bottom 100 and may have an opening through one of the ends through which moisture may be applied to the absorbent material within.

Referring to Figs. 7 to 10, the cigar case is made of two parts A' hinged together, and in 105 each of which parts the cigars are adapted to be arranged vertically. Each of these parts corresponds substantially to the case shown in

Fig. 1, but is made with a metallic frame by which the two parts are connected. In the bottom of each of these parts A', a humidor B is located as in Fig. 1, but in this case the arms E are made of wire as shown at E² in place of being made of flat metal indicated in Figs. 1 and 2 because the shape of the leather portion of the case A' is better adapted to receive the arms E² in round cross section than the flat metal; otherwise the construction is substantially the same as in the case of Fig. 1.

In all of these uses of my invention, it will be observed that the humidor is arranged within the case and in a position to supply moisture to the cigars to keep them in a properly moist condition. Moreover the humidor is of substantially the thickness of the case, so that the case would not be crushed at the bottom. Furthermore, in those cases where the humidor is provided with one or more arms, the same are employed to keep the humidor in its proper position within the case and at the same time enable it to be withdrawn when it is desired to introduce moisture.

I do not restrict myself to the minor details of the humidor as it would be made in shape to adapt it to the particular form of cigar case with which it is to be combined, but in all cases it is necessarily very narrow so as to snugly fit within the case close to the walls thereof so as not to interfere with the ordinary normal use of the case as a carrier for the cigars; therefore, while I prefer the construction shown, I do not limit myself to the details thereof as these may be modified without departing from the spirit of the invention.

Having now described my invention, what I claim as new, and desire to secure by Letters Patent is:—

1. A pocket cigar case permanently closed on the bottom, combined with a humidor arranged in the bottom thereof and upon which the ends of the cigars directly rest.

2. A pocket cigar case, combined with a humidor arranged in the bottom thereof and upon which the ends of the cigars rest provided with two arms respectively extending along the opposite ends of the case.

3. A pocket cigar case, combined with a humidor arranged in the bottom thereof and upon which the ends of the cigars rest provided with two spring arms respectively ex-

tending along the ends of the case and spring 55 pressed outwardly to fit tightly to the case.

4. A pocket cigar case formed of soft material combined with a humidor fitted within its interior and close to the bottom and having two arms of flat metal fitting close to 60 the ends of the case and acting to stiffen it and prevent its being crushed.

5. A pocket cigar case of flexible material, closed at the bottom, and provided with a detachable arrangement wholly within the 65 case, and resting on the bottom, and having an arm secured to one end of the humidor co-operating with the side of the case to hold the humidor in position.

6. A removable humidor for a pocket 70 cigar case, consisting of a moisture pad, provided with an arm integral with it extending therefrom at substantially right angles for the adjusting and removing of the humidor relative to the case.

7. A removable humidor for a pocket 75 cigar case consisting of a moisture carrying part provided with two arms respectively extending therefrom at opposite ends for co-operating with the case and for holding the 80 humidor in position.

8. A humidor for a pocket cigar case consisting of a plate B having the bent-in sides b combined with a moisture pad F held by the bent-in side parts, and spring arms extending 85 from the ends of the plate B for holding it in position within the case.

9. A removable humidor for a cigar case consisting of a long flat moisture carrying pad provided with an arm extending therefrom at right angles to the length of the moisture carrying pad, and in the same plane with the humidor for adjusting it within the case.

10. A pocket cigar case open only at the 95 top, combined with a humidor of flat construction arranged within the case and detachably supported close to the surface of the materials constituting the wall or body of the case so as not to interfere with the normal 100 use of the case as a carrier of cigars.

In testimony of which invention, I have hereunto set my hand.

JONAS LANGFELD.
